The ornamental design for medical simulator board with training pieces set, as shown and described.

DESCRIPTION

FIG. 1 is a top perspective view of a medical simulator piece, shown separately for clarity of illustration;

FIG. 2 is a bottom perspective view of the medical simulator piece of FIG. 1;

FIG. 3 is another bottom perspective view of the medical simulator piece of FIG. 1;

FIG. 4 is a front view of the medical simulator piece of FIG. 1; back view being a mirror image;

FIG. 5 is a top view of the medical simulator piece of FIG. 1;

FIG. 6 is a bottom view of the medical simulator piece of FIG. 1;

FIG. 7 is a top perspective view of a medical simulator piece, shown separately for clarity of illustration;

FIG. 8 is a bottom perspective view of the medical simulator piece of FIG. 7;

FIG. 9 is a front view of the medical simulator piece of FIG. 7; back view being identical;

FIG. 10 is a side view of the medical simulator piece of FIG. 7; other side view being identical;

FIG. 11 is a top view of the medical simulator piece of FIG. 7;

FIG. 12 is a bottom view of the medical simulator piece of FIG. 7;

FIG. 13 is a top perspective view of a medical simulator piece, shown separately for clarity of illustration;

FIG. 14 is a bottom perspective view of the medical simulator piece of FIG. 13;

FIG. 15 is another bottom perspective view of the medical simulator piece of FIG. 13;

FIG. 16 is a side view of the medical simulator piece of FIG. 13;

FIG. 17 is a top view of the medical simulator piece of FIG. 13;
FIG. 18 is a bottom view of the medical simulator piece of FIG. 13;
FIG. 19 is a top perspective view of a medical simulator piece, shown separately for clarity of illustration;
FIG. 20 is a bottom perspective view of the medical simulator piece of FIG. 19;
FIG. 21 is a front view of the medical simulator piece of FIG. 19; back view being identical;
FIG. 22 is a side view of the medical simulator piece of FIG. 19; other side being identical;
FIG. 23 is a top view of the medical simulator piece of FIG. 19;
FIG. 24 is a bottom view of the medical simulator piece of FIG. 19;
FIG. 25 is a top perspective view of a medical simulator piece, shown separately for clarity of illustration;
FIG. 26 is a front view of the medical simulator piece of FIG. 25; back view being identical;
FIG. 27 is a side view of the medical simulator piece of FIG. 25; other side view being a mirror image;
FIG. 28 is a top view of the medical simulator piece of FIG. 25;
FIG. 29 is a bottom side view of the medical simulator piece of FIG. 25;
FIG. 30 is a top perspective view of a medical simulator piece, shown separately for clarity of illustration;
FIG. 31 is a bottom perspective view of the medical simulator piece of FIG. 30;
FIG. 32 is a side view of the medical simulator piece of FIG. 30; other side view being identical;
FIG. 33 is a front view of the medical simulator piece of FIG. 30; back view being identical;
FIG. 34 is a bottom view of the medical simulator piece of FIG. 30;
FIG. 35 is a top view of the medical simulator piece of FIG. 30;
FIG. 36 is a top perspective view of a medical simulator piece, shown separately for clarity of illustration;
FIG. 37 is a bottom perspective view of the medical simulator piece of FIG. 36;
FIG. 38 is a front view of the medical simulator piece of FIG. 36; back view being identical;
FIG. 39 is a side view of the medical simulator piece of FIG. 36; other side view being identical;
FIG. 40 is a top view of the medical simulator piece of FIG. 36;
FIG. 41 is a bottom view of the medical simulator piece of FIG. 36;
FIG. 42 is a bottom perspective view of a medical simulator piece, shown separately for clarity of illustration;
FIG. 43 is a top perspective view of the medical simulator piece of FIG. 42;
FIG. 44 is a side view of the medical simulator piece of FIG. 42;
FIG. 45 is a top view of the medical simulator piece of FIG. 42;
FIG. 46 is a bottom view of the medical simulator piece of FIG. 42;
FIG. 47 is a top perspective view of a medical simulator board, shown separately for clarity of illustration;
FIG. 48 is a bottom perspective view of the medical simulator board of FIG. 47;

FIG. 49 is a side view of the medical simulator board of FIG. 47; other side being identical;
FIG. 50 is a front view of the medical simulator board of FIG. 47; rear view being identical;
FIG. 51 is a top view of the medical simulator board of FIG. 47;
FIG. 52 is a bottom view of the medical simulator board of FIG. 47;
FIG. 53 is a top perspective view of a medical simulator piece, shown separately for clarity of illustration;
FIG. 54 is a bottom perspective view of the medical simulator piece of FIG. 53;
FIG. 55 is a front view of the medical simulator piece of FIG. 53;
FIG. 56 is a rear view of the medical simulator piece of FIG. 53;
FIG. 57 is a top view of the medical simulator piece of FIG. 53;
FIG. 58 is a left side view of the medical simulator piece of FIG. 53;
FIG. 59 is a right side view of the medical simulator piece of FIG. 53;
FIG. 60 is a bottom view of the medical simulator piece of FIG. 53;
FIG. 61 is a top perspective view of a medical simulator piece, shown separately for clarity of illustration;
FIG. 62 is a bottom perspective view of the medical simulator piece of FIG. 61;
FIG. 63 is a top view of the medical simulator piece of FIG. 61;
FIG. 64 is a bottom view of the medical simulator piece of FIG. 61;
FIG. 65 is a bottom back view of the medical simulator piece of FIG. 61;
FIG. 66 is a left side view of the medical simulator piece of FIG. 61;
FIG. 67 is a right side view of the medical simulator piece of FIG. 61;
FIG. 68 is a top perspective view of a medical simulator piece, shown separately for clarity of illustration;
FIG. 69 is a bottom perspective view of the medical simulator piece of FIG. 68;
FIG. 70 is a top view of the medical simulator piece of FIG. 68;
FIG. 71 is a rear view of the medical simulator piece of FIG. 68;
FIG. 72 is a front view of the medical simulator piece of FIG. 68;
FIG. 73 is a right side view of the medical simulator piece of FIG. 68; left side view being identical;
FIG. 74 is a bottom view of the medical simulator piece of FIG. 68;
FIG. 75 is a top perspective view of a medical simulator piece, shown separately for clarity of illustration;
FIG. 76 is a front view of the medical simulator piece of FIG. 75; rear view being a mirror image;
FIG. 77 is a side view of the medical simulator piece of FIG. 75; other side being identical;
FIG. 78 is a top view of the medical simulator piece of FIG. 75;
FIG. 79 is a bottom view of the medical simulator piece of FIG. 75;
FIG. 80 is a top perspective view of a medical simulator piece, shown separately for clarity of illustration;

FIG. 81 is a bottom perspective view of the medical simulator piece of FIG. 80;
 FIG. 82 is a front view of the medical simulator piece of FIG. 80;
 FIG. 83 is a back view of the medical simulator piece of FIG. 80;
 FIG. 84 is a right side view of the medical simulator piece of FIG. 80; left side view being a mirror image;
 FIG. 85 is a top view of the medical simulator piece of FIG. 80;
 FIG. 86 is a bottom view of the medical simulator piece of FIG. 80;
 FIG. 87 is a bottom perspective view of a medical simulator piece, shown separately for clarity of illustration;
 FIG. 88 is another bottom perspective view of the medical simulator piece of FIG. 87;
 FIG. 89 is a front view of the medical simulator piece of FIG. 87;
 FIG. 90 is a back view of the medical simulator piece of FIG. 87;
 FIG. 91 is a top view of the medical simulator piece of FIG. 87;
 FIG. 92 is a left side view of the medical simulator piece of FIG. 87;
 FIG. 93 is a right side view of the medical simulator piece of FIG. 87;
 FIG. 94 is a bottom view of the medical simulator piece of FIG. 87;
 FIG. 95 is a top perspective view of the medical simulator board with training pieces set in accordance with our new design.
 FIG. 96 is a bottom perspective view of the medical simulator board with training pieces set of FIG. 95.
 FIG. 97 is a front view of the medical simulator board with training pieces set of FIG. 95.
 FIG. 98 is a back view of the medical simulator board with training pieces set of FIG. 95.
 FIG. 99 is a right side view of the medical simulator board with training pieces set of FIG. 95.
 FIG. 100 is a left side view of the medical simulator board with training pieces set of FIG. 95.

FIG. 101 is a top view of the medical simulator board with training pieces set of FIG. 95; and,
 FIG. 102 is a bottom view of the medical simulator board with training pieces set of FIG. 95.
 The dash-dash broken lines in the drawings depict portions of the medical simulator board with training pieces set that form no part of the claimed design.
